UNITED STATES PATENT OFFICE

2,164,636

BUILDING COVERING

Edward R. Black, Chicago, Ill.

Application January 12, 1933, Serial No. 184,633

10 Claims. (Cl. 108—3)

My invention relates to building coverings,—the weather-proof sheathing applied to roofs and exterior walls for protection against the weather and for decorative purposes.

5 A widely used variety of such sheathing—frequently and herein referred to as "prepared roofing"—consists of a flexible asphaltum impregnated paper stock or "felt" sheet which is covered by a layer of asphalt, or other similar 10 suitable material, and often surfaced with granular material for purposes of decoration and additional protection.

Such roofing material is applied or laid in units which may take the form of individual or multiple shingles or long strips. Because of the inherent flexibility of the material it is highly desirable to anchor the units near the exposed edges or butts so as to keep them from being blown up and torn or broken by the wind. It is also highly 20 desirable that metallic anchorages—usually nails—used to hold down the exposed edges or butts be unexposed to sun and weather. The undesirable and injurious results flowing from exposed anchorage nails are too well known to 25 require repetition and for years various forms of units, arrangements and methods of laying, for covering and concealing the butt anchorage nails, have been proposed and used.

One of the objects of my invention is to provide 30 an improved building covering.

Another object is to provide a simple and easily manufactured and applied covering unit for effectively covering and concealing the butt anchorage nails.

35 A further object is to provide a unit that readily lends itself to a method of application wherein the roof or wall may be covered progressively in a direction the reverse of that heretofore employed, e. g., on a roof from ridge to eave instead of from eave to ridge.

40 Other objects and advantages will hereinafter appear.

In the drawings:

Fig. 1 is a plan view of a portion of a roof or 45 side wall of a building, showing the improved units formed for conventional laying to produce the well-known hexagonal appearance;

Fig. 2 is an enlarged vertical section on the line 2—2 of Fig. 1;

50 Fig. 3 is an enlarged top plan—open or unfolded—of a hexagonal shingle such as may be used to produce the effect shown in Fig. 1;

Fig. 4 is a plan of a strip of prepared roofing material showing how such units may be effectively cut therefrom;

Fig. 5 is a plan view of a portion of a roof or side wall of a building, showing another conventional (inverted T) effect;

Fig. 6 is a plan view of a shingle used to produce the effect shown in Fig. 5;

Fig. 7 shows how these units may be effectively cut from strips of prepared roofing stock;

Fig. 8 is a front elevation of a portion of the building side wall covered with my improved units, formed and figured to simulate brick 10 work;

Fig. 9 is a front view—open or unfolded—of a unit suitable to produce the effect shown in Fig. 8;

Fig. 10 is a front view of a portion of a wall 15 covered with a modified form of unit to simulate brick work;

Fig. 11 is a perspective view—open or unfolded—of the unit used in Fig. 10;

Fig. 12 is a plan view of a portion of a roof 20 showing how shingle units incorporating the features of this invention may be laid from ridge to eave, rather than in the heretofore universally conventional method of laying them from eave to ridge;

Fig. 13 is a plan view—open or unfolded—of a unit suitable for this method of laying a building covering, and

Fig. 14 is a plan view of the unit shown in Fig. 13 folded and ready for application.

In general, my improved covering unit comprises a body portion, the lower part of which is exposed, and a turned-under portion along the exposed or butt edge of the unit; the body portion being provided with an opening or recess through which the shank and head of an anchoring nail may be driven to pass the shank through the underlying turned-back portion (which forms the anchorage strip) and into the building framework without necessitating any distortion 35 or alteration (such as unfolding) of the unit; and after the nails are driven through the anchorage strip the heads thereof, which up to this time are exposed through the recess in the body portion, are covered and effectively masked by 45 pieces or strips of roofing material slipped into place between the body and turned-under portion behind the recess of the body portion and in front of and over the nail head lying against the under-turned portion.

50 Referring first to Fig. 1, the section of building covering therein shown illustrates the conventional laying (e. g., from eave to ridge) of my improved units in hexagonal shape and the general appearances of the covering when so laid. 55

In general, the shingle units are arranged on the building wall or roof to be covered in the usual way,—horizontally aligned to form courses, the units of all courses except the first and last 5 overlapping the upper portions of preceding course units and being in turn partly overlapped by the lower portions of units in succeeding courses. Beginning at the bottom or eave, the laying proceeds course upon course until the top 10 or ridge is reached. Thus, for example, the shingles forming a horizontal course A have their tips overlapped by the butts of shingles in the higher course C and, in turn, the tips of shingles in the course B are overlapped by the butts of shingles in the next higher course D. Of course, 15 some of the upper portions of the units in course A are overlapped by lower portions of units in course B, and upper portions of units in course B are overlapped by portions of units in course C, etc.

20 Referring now particularly to Figs. 2 and 3, each shingle unit has a body portion 5 and a turned- or folded-under portion 6 adjacent the butt edge. The turned-under portion 6, as will 25 be hereinafter described, forms an anchor or nailing strip through which a nail may be driven into the underlying building framework to anchor down the butt. The body portion is provided with an opening 7 therethrough so as to 30 expose from the front a small area of the under-turned portion or nailing strip for the purpose of permitting the shank and the head of a nail to be driven therethrough from the front side of the unit.

35 Although the nail-receiving opening through the shingle body portion may be variously located in the butt region in front of the nailing strip, I prefer to locate it adjacent the fold and form it to extend into the fold uniting the body 40 and turned-under portions, as shown most clearly in Fig. 2. By locating the nail-receiving opening in this relation to the fold, the fold is, in effect, removed for the width of the opening and does not form a pocket therebelow in which moisture 45 can collect. This opening, which needs be only large enough to accommodate the head of the anchoring nail and permit the nail to be driven home until its head comes tightly against the anchoring strip 6 without the face of the unit 50 body portion being damaged, is preferably, as indicated in Fig. 3, formed before the unit is folded. Then the unit is folded back along the line a—b indicated in Fig. 3, so that the anchor strip 6 lies quite tightly behind and substantially parallel to 55 the body portion 5.

Because of the fact, as will be presently explained, that the units do not need to be opened or unfolded during the process of laying and anchoring them, they may be folded at the factory while warm and under conditions and with machinery that will insure a straight, clean and undamaging fold. And since the line of fold 60 forms the extreme butt edge of a unit and there are two thicknesses of material at that region, the units not only present an appearance of depth 65 and thickness of exposure, but they are, as a matter of fact, reinforced and especially strong in the region of the extreme butt edge where the greatest strain comes from the action of the 70 wind, etc.

75 When such a shingle has been placed in its position on the roof or wall, the butt edge is anchored down by a nail 8 applied from the front to the anchor strip 6 through the opening 7 in

from the front by a hammer or other suitable tool, until the head tightly engages and clamps down the anchor strip. Then to complete the unit a small closure in the form of a piece of suitable material 9 is slipped in between the body and turned-under portions, as indicated at the upper right-hand corner of Fig. 1, and pushed along and down into the apex of the fold until it completely blocks the nail-receiving opening of the body portion and covers and conceals the head 10 of the anchoring nail which was applied therebehind through the anchor strip. It may be necessary, if the body and anchor strip portions are pressed very tightly together slightly to separate them,—for example, by slightly raising the body 15 portion after the anchor strip has been nailed down—in order easily and quickly to position the closure piece. However, since such bending on the job needs be only a few degrees, it will not injure the unit—at the fold or elsewhere—even in 20 cold weather. Preferably the closure pieces are of the same material, color and finish as the shingles so that when they are in position to block the nail-receiving openings and cover the heads of the butt anchorage nails, they will effectively mask the openings and the fact that there 25 are openings through the exposed shingle body portions will be hardly noticeable. It will be unnecessary to anchor the closure pieces in position behind the body portion, because the normal- 30 ly close relation between the anchor strip and body portion and the adhesiveness of the asphalt will prevent their displacement. Displacement will be further guarded against if, as is usually the case, one surface of the closure piece is coated 35 with granular material to match the exposed surface of the shingle. After the masking pieces are inserted, the upper or tip region of each unit may, if desired, be anchored down by nails driven therethrough above the line of overlap of the 40 units constituting the next higher course.

As an aid in retaining the units in place, to obviate undue thickness of the covering in the butt regions and in order to facilitate the proper 45 positioning of the units to insure uniformity of design, various arrangements may be used. For example, each side edge may be formed with small triangular projections 10 and the upper edge may be formed with a notch or recess 11, which preferably is of the same length horizontally as the outer edge of the anchor strip 6. With the units in this form the projections 10 of adjacent units of a course form, in effect, a socket or crotch into which the turned-under anchor strip of the intermediate unit of the next higher 50 course will fit. Such interfitting of units in successive courses prevents the anchor strips of the units of one course from lying upon the units of the preceding course and thereby not only improves the appearance of the roof when finished, 60 but also serves to aid in the proper positioning of units and in keeping them in place.

Fig. 4 shows how such units may be conveniently cut from sheets of roofing material with but little waste.

In applying the covering or sheath, the laying of these units proceeds upwardly in the conventional way from bottom to top (e. g., from eave to ridge). As the succeeding units of each horizontal course are laid, the butts thereof are securely and tightly anchored down to the building by driving nails, from the front side, through the openings 7 until the nail heads are inside of the plane of the rear surface of the body portions and tightly against—perhaps even slightly em- 70 75

bedded into—the underlying turned-under portions 6. Next, the masking or covering pieces 9 are inserted between the body portions and anchor strips and shoved into the apices of the 5 folds until the openings are completely backed and the nail heads masked thereby. Then the tip of each unit in the course may, if desired, be anchored down by driving nails therethrough in the regions that will be covered by the units of the 10 succeeding course. Many times such tip anchoring nails will be unnecessary, because the butt anchoring nails of the higher courses pass through the tips of the units of lower courses. After one course is thus laid, the units of the next 15 higher or succeeding course are similarly laid and anchored down; and this procedure is continued until the entire roof or wall is covered.

Fig. 5 illustrates the conventional sequence of laying units to produce another typical design (inverted T); Fig. 6 shows a suitable unit for this 20 purpose; and Fig. 7 illustrates how such units may be cut from sheet roofing material.

Looking first at Fig. 6, each unit has a body portion 15 and a turned-under portion 16 forming an underlying anchor strip. The body portion has a hole or recess 17 which, preferably as 25 previously described, extends into the fold line *a*—*b* between the body and turned-under portions. Each unit is completed by a masking piece 30 19 (see Fig. 5) inserted between the body and turned-under anchoring portions to cover the head of the butt anchoring nail 18. Preferably the anchoring strip 16 is made somewhat narrower than the butt edge of the unit and its lateral edges 22—23 are flared outwardly. And the 35 upper edge of the unit is provided with a recess 21 which is complementary to the anchor strip 16, while the lateral edges have small notches 20 cut therein.

40 In laying units of this shape in the conventional manner (i. e., with the units of adjacent courses staggered), the anchor strips of units of one course lie between the lateral edges of units in the preceding course and the notches 20 of adjacent units in the same course may receive the outer corners of the anchor strips 16 of the intermediate overlapping units of the next higher course. Thus, the interfitting of the anchor strips with the lateral edge notches of units of the preceding course serves to prevent the anchor strips of the units of one course from lying upon the unit of the preceding course, helps in placing the units in proper position relative to others, and provides a covering of better appearance and 55 more substantial construction.

Fig. 7 shows how units of this shape may be cut from sheet roofing with little waste. The recess or notch 21 in the upper edge of the unit, which results from the removal of material to 60 form the anchor strip of another unit—is not objectionable because, when units are laid, the upper portions are sufficiently overlapped and covered by the butt portions of units in higher courses.

Fig. 8 shows how units, preferably in the form 65 of strips, may be laid to simulate the appearance of courses of brick work. Fig. 9 shows a satisfactory form in which such units may be produced.

70 Referring first to Fig. 9, which shows the unit unfolded as it is cut from sheet material, there is a body portion 25 and an anchor portion 26, which is folded back along the line *a*—*b* to lie closely under or behind the body portion. Body portion 25 has openings or recesses 27 cut there-

in adjacent the line of fold, such recesses or openings being, as heretofore described, for the purpose of permitting nails to be applied from the front through the anchor portion without actually passing through or touching the body portion. 5 The number and spacing of such nail-receiving openings in the body portions of the units can be varied as conditions may require or seem to render advisable.

In order to simulate brick work the outer or 10 what will be the exposed surface of the body portion may be provided with a horizontal stripe 30 of a width and color to look like a layer of mortar. Similar vertical stripes 31 simulate the up and down mortar fillings. These colored stripes 15 may be provided in various ways, such as by printing, painting or embossing, or by any other suitable process,—preferably during the fabrication of the sheet stock before units are cut therefrom. As I prefer to make the unit, a nail-receiving opening 27 is provided through the body portion at the lower or fold end of each mortar simulating stripe 31 thereon, and of substantially 20 the same width as the stripe. The purpose of so locating and proportioning the nail-receiving 25 recesses will presently appear.

In order that horizontally aligned units may be effectively fitted together, I prefer to make the lateral edges complementary to each other. Thus, the edge 32 is stepped inwardly and includes an 30 edge recess 27' whereas the edge 33 is stepped outwardly and includes an edge recess 27''. A mortar simulating stripe 31', which is of the same width as the partial recess 27' and consequently narrower than the full stripe, extends upwardly 35 from the edge recess 27'. A similar narrow stripe 31'' extends upwardly from the edge recess 27''. Now, when two such units are placed end to end, the right-hand end of one fits into or dovetails with the left-hand end of the other and the partial or edge recesses 27'—27'' of abutting units form together a recess or nail-receiving opening 40 of full width like those in the intermediate regions of the body portion. Similarly, the complementary partial mortar simulating strips 45 31'—31'' of adjacent units form a full width vertical mortar simulating stripe.

Units of this type are completed by applying nail-masking strips or pieces 29 between the body and anchor portions behind the openings through 50 the body portions and over the heads of the nails driven through the anchor portions. By making the front or exposed surface of such masking pieces or strips of the same color and material as the mortar simulating stripes on the body portion, they will, when positioned, complete or fill in the vertical stripes where the same were interrupted by the nail-receiving recesses and the simulation of brick work will be completed. Although the masking elements may be provided in 55 the form of small pieces only somewhat larger than the nail-receiving recesses through the body portion, I prefer to provide them in the form of long strips.

Units of this type are laid in the same manner 65 as previously described. The units of one course overlap those of the preceding course so that the overlying butt edge comes at least down to the top edge of the horizontal stripe. Where two units of a course come together, two nails should 70 be applied through the opening formed by the complementary edge recesses, one nail being driven into the corner of the anchor strip of each unit. Both of these nails will, of course, be covered by the masking units in precisely the same 75

way as the nails passed through the other body recesses are covered.

Figs. 10 and 11 show another form for units constructed and colored to simulate brick work. In this unit there is provided a body portion 35 and a turned-back underlying anchor strip 36. In this construction the nail-receiving recesses in the body portion are provided by slots 37 which extend from the upper or tip edge down to the line of fold *a*—*b*. The horizontal mortar simulating stripe is located along and adjacent the upper edge. In this instance the masking strip 38 is made deep enough to underlie the slots 37 throughout their length. After the butt-anchor-

ing nails have been applied, as previously described, the masking pieces are inserted between the body and anchoring portions. If the exposed surfaces of these masking strips are colored and finished to simulate mortar, the part exposed through the nail-receiving recesses will provide the simulation of the vertical mortar fillings of brick work.

The units hereinbefore described are typical of those adapted for laying in the heretofore accepted manner; that is, in courses succeeding each other from the bottom upwardly. I shall now describe a unit which typifies those that lend themselves to laying in the opposite direction; i. e., in courses succeeding each other from the top downwardly. And so far as I am aware, I am the first to propose a unit that may be laid in this reverse manner and afford adequate protection against entrance of moisture.

The laying of building covering units in courses from the top downwardly (e. g., from ridge to eave) presents an advantage over the present standard method which is of decided importance. That advantage is this: It is unnecessary for the workman to work upon and over the part that has been covered. Thus, in laying roofing in the heretofore conventional manner, the workman always has the completed work under and behind him. He must stand, kneel or lie upon, and supplies reach him over, the finished portion of the roof. If he requires cleats and so forth to hold him and his supplies, they must be nailed through roofing that is already laid. There is always the hazard that the covering will be damaged,—particularly when it is composed of relatively tender material such as prepared roofing.

On the other hand, by laying units in the opposite direction, the workman can always have uncovered roof beneath him. He can stand, lie and kneel upon and have his supplies passed over what is to be covered rather than what has been covered. Usually the parts uncovered can remain unmolested. The hazard of accidental injury during the progress of laying the covering will be greatly reduced.

An unfolded unit, as it is cut from the sheet of stock, is shown in Fig. 13; Fig. 14 shows the unit folded with a masking strip interposed between the body and anchor portions.

Here, again, the unit has a body portion 43 and an anchoring portion 44,—the latter being turned under along the fold line *a*—*b*. The edge defined by the fold *a*—*b* constitutes the exposed or butt edge of the unit. In this instance I provide two nail-receiving openings 47 through the body portion,—one near each lateral edge thereof. The upper portion of the unit is tapered inwardly so that for a considerable distance below its upper or tip edge the width is less than the spacing between the nail-receiving openings. This arrangement permits lower course units to

be applied after upper course units have been positioned and nailed at the butts and still permit the tips of units in lower courses to be inserted underneath the preceding course units to afford adequate protection against entrance of moisture, as will be presently explained.

Fig. 12 illustrates the laying of such units in a direction from the top downwardly. For example, the units of a top course D are first positioned and secured in place by nails driven through their body portions near the tips. Then the units of the next lower course E are positioned in staggered relation to the units of course D. This is done by first inserting their tips below the butts of the D course units and then pushing them upwardly below the D course units until they are sufficiently overlapped by the D course units. When a unit of the E course has been thus located in the desired position, the butts of the overlapping units in the D course are anchored down by nails applied through its nail-receiving recesses and driven through the anchoring strip into the building framework in precisely the same manner as hereinbefore described. These nails, which anchor down the butts of the D course units, pass through the upper covered tip portions of the units in the E course and thus serve to hold the E course units in place until the units of the F course have been positioned. After the butt anchoring nails have been applied to a unit of D course, the small masking piece 49 is inserted between the body and turned-under anchoring portions and pushed into place until it covers the nail heads and completely masks the openings through the body thereof.

After the E course units have been secured at their tips by the butt anchoring nails of the D course units, then the F course units are positioned in precisely the same way as was explained for the E course units; and when they are positioned, the butts of the E course units may be nailed down and the nails and recesses masked as previously explained. These butt nails of the E course units pass through the tip portion of the F course units so that they will be held while units of the G course are positioned. This procedure continues until the whole roof or wall is covered. By tapering the tip portions of the units, as previously described, the units may be pushed upwardly under overlying units until the tips lie between the butt anchoring nails of units and underneath the butt portions of units in the second course thereabove, i. e., the second preceding course, as shown by the dotted lines in Fig. 12, and insure adequate lap and covering underneath the junction of the butt edge of units of one course and the space between adjacent units of the next lower course. Of course, as will be obvious, there is not sufficient space above to enable the units in the top two courses—e. g., the two courses immediately below the roof ridge—to have their tip portions thus positioned underneath units in a second course thereabove because, as to them, there is no second course thereabove. Adequate protection at the ridge, however, can be attained by employing the usual ridge strips.

Having thus illustrated and described the nature and several embodiments of my invention, what I claim and desire to secure by United States Letters Patent is as follows:

1. A building covering unit comprising a body portion; an anchoring portion turned under the body portion at one edge thereof, said body por-

tion having a recess therethrough to the underlying anchor portion through which recess a nail may be applied through the anchor portion into the building framework without altering the normal relative positions of the body and anchor portions; and a nail-concealing unit for application between the body and anchor portions behind the recess in the body portion to cover the nail.

10 2. A building covering unit comprising a body portion; an anchor portion folded under the body portion along one edge thereof, said body portion having a recess therein which is backed by the anchor portion and through which a nail may be applied from the front of the unit and driven through the anchor portion into the building framework, said recess extending to the fold between the body and anchor portions; and a nail-concealing piece insertable between the body and anchor portions to mask the recess through the body portion and cover any nail driven through the anchor portion back of the recess.

15 3. The method of applying building covering units in staggered and overlapping and underlapping relation which consists in starting the positioning of the units at the top and progressing downwardly toward the bottom of the area to be covered, and applying anchorage means through the units into the building framework, 20 some of said anchorage means passing through temporarily exposed areas of upper units and unexposed areas of lower units.

25 4. A building covering unit consisting of a sheet of roofing material folded to form an edge and overlying body and underlying anchor portions, the overlying body portion having a recess for the passage of a fastening means into the anchor portion; and a concealing piece to lie between the body and anchor portions to cover 30 the fastening means.

35 5. A building covering unit comprising a body portion, and an underlying anchor portion formed by folding a sheet of roofing material along a line, said line of fold constituting the butt edge of the unit and the body portion having an opening therethrough in front of the underlying anchor portion, said opening serving to permit a nail to be driven from the front through only the anchor portion; and a nail-covering piece for application between the body and anchor portions behind the opening through the body portion to mask a nail driven through the anchor portion behind the opening in the anchor portion.

40 55 6. A building covering consisting of a plurality of overlapping units, each unit comprising a body portion and an under-turned anchor portion wherein the anchor portion has a part exposed through the body portion for the application of anchoring means therethrough into the building framework; anchoring means applied through the exposed parts of the anchor portions of the units into the building framework; and concealing units applied between the body and an-

chor portions over the anchoring means to cover the same.

7. The method of laying in vertically overlapping horizontal courses building covering units having upper tip portions which are covered by units in preceding courses and lower butt portions which are exposed after the units are laid, such method consisting in applying the units to form courses succeeding each other from the top downwardly, inserting the tip portions of units 10 constituting one course underneath the butt portions of units forming the next preceding course until such tip portions of units in all courses except the top two courses lie underneath butt portions of units of the second preceding course, 15 and anchoring the tip portions of the units by nails applied through the exposed butt portions of units in the next preceding course.

8. The method of laying in vertically overlapping horizontal courses building covering units 20 having upper tip portions which are covered by units of preceding courses and lower butt portions which are exposed after the units are laid, such method consisting in applying the units to form the courses succeeding each other from the 25 top downwardly, the tip portions of all units in courses except the top two courses lying underneath butt portions of units in the second preceding course, and anchoring the tip portions of the units by nails applied through the butts of 30 units of the immediately preceding course.

9. The method of laying in vertically overlapping horizontal courses building covering units having upper tip portions which are covered by units of preceding courses and lower butt 35 portions which are exposed after the units are laid, such method consisting in applying the units to form the courses succeeding each other from the top downwardly, the tip portions of all units in courses except the top two courses lying underneath butt portions of units in the second preceding course, anchoring the tip portions of the units by nails applied through the butts of units of the immediately preceding course, and masking the heads of the nails after they have been 40 thus applied.

10. The method of laying in vertically overlapping horizontal courses building covering units having upper tip portions which are covered by units in preceding courses and lower butt 50 portions which are exposed after the units are laid, such method consisting in applying the units to form courses succeeding each other from the top downwardly, inserting the tip portions of units 55 constituting one course underneath the butt portions of units forming the next and second preceding courses until such tip portions of units in all courses except the top two courses lie underneath butt portions of units of the second preceding course, and anchoring the tip portions of the units constituting a horizontal course by nails applied therethrough above the line of permanent exposure.

EDWARD R. BLACK.
